UNITED STATES PATENT OFFICE.

PEDER FURUSETH, OF EDMORE, NORTH DAKOTA.

RAILWAY-MOWER.

1,086,236.

Specification of Letters Patent. Patented May 12, 1914.

Application filed September 17, 1913. Serial No. 799,268.

To all whom it may concern:

Be it known that I, PEDER FURUSETH, a citizen of the United States, residing at Edmore, in the county of Ramsey and State of North Dakota, have invented certain new and useful Improvements in Railway-Mowers, of which the following is a specification, reference being had to the accompanying drawings.

10 This invention relates to new and useful improvements in railway mowers and more particularly to a device for removing the weeds and the like from points immediately adjacent the railway ties and the primary 15 object is to provide a device of this character which will effectively carry out the purpose for which the same is designed.

A further object of the invention resides in providing an improved mower which will 20 be readily actuated for disposition to various positions with respect to the truck carrying the same and a still further object resides in providing a device which is simple and durable in construction, inexpensive to 25 manufacture and one which will be very efficient and useful in operation.

With these and other objects in view, the invention consists in the novel features of construction, combination and arrangement 30 of parts as will be hereinafter referred to and more particularly pointed out in the specification and claims.

In the accompanying drawings forming a part of this application, Figure 1 is a 35 front elevation of the device. Fig. 2 is a plan view thereof. Fig. 3 is a section as seen on line 3—3, of Fig. 2. Fig. 4 is a plan view, on an enlarged scale, of the device with the deck or platform of the device removed; 40 and Fig. 5 is a perspective view of the supporting means for the mower.

In describing my invention, I shall refer to the drawings in which similar reference characters designate corresponding parts 45 throughout the several views and in which 1 indicates a railway truck of the usual or any preferred type mounted on the rails 2 and mounted on said truck is a deck or platform 3. The rear axle 4 of the device has 50 an enlarged pulley 5 carried thereon, over which extends an endless belt 6, the same being disposed longitudinally under the deck or platform 3, and a transverse shaft 7 rotatably mounted in the bearings 8 at the forward end of the truck, in the rear of the

front axle 9, also has a pulley 10 mounted thereon, over which is extended said belt 6. The one end of the shaft 7 is provided with an enlarged bevel gear 11 which is rotated by a means to be presently described, where- 60 by the truck may be propelled.

Mounted on the platform or deck 3, is an engine 12, the crank shaft 13 of which has a clutch pulley 14 carried thereon, over which is extended an endless belt 15. This clutch 65 pulley is disposed to its effective and ineffective position through the medium of the lever 16 and the belt 15 has the reaches thereof extended through slots 17 formed in the deck or platform, whereby to be engaged with an operating means therebelow. A shaft 18 is mounted in bearings 19 on a transverse bar of the truck 1, said shaft 18 extending longitudinally thereof and provided with a pulley 20 which also receives 70 thereover the belt 15. This shaft 18 is provided, at the forward end thereof, with a bevel pinion 21 which meshes with the enlarged bevel gear 11, and it will thus be seen through the intermediate means, that the 75 rear axle 4 may be driven through the operation of the engine.

My invention primarily contemplates the provision of a mower in connection with this truck, said mower to be operated by the 80 same means for the propulsion of said truck, and to this end, a pair of cross arms 22 are provided, the inner ends of which are pivotally mounted on brackets or keepers 23 on the one side bar of the truck 1. The outer 85 ends of these cross arms 22 are engaged with a skid plate or the like 24 to which is secured a mower 25, of the usual or any preferred type. Secured to the cross arms 22 at the point of intersection, is the one end 90 of a strong coil spring 26 and engaged with the opposite end of said coil spring is a chain 27, which chain is also adjustably engaged with a hook or the like 28 on the platform 3 and through this medium, said 95 mower is yieldingly supported from the truck.

Fulcrumed on a bracket or projection on one of the arms 22, is a lever 29 and pivoted to said lever, intermediate of its ends, is a rod 30, the outer end of which is pivotally engaged with an arm 31 which extends vertically from the skid plate 24. A ratchet 32 is formed in connection with the bracket 100 which supports the lever 29 and a spring de- 110

tent is arranged in connection with said lever for engagement with the ratchet, whereby to retain said lever in various adjusted positions. It will be seen that through the medium of this lever, the mower may be raised and lowered to various positions, as will be seen in Fig. 1 and the same held in such position by the engagement of the device with the ratchet. The device in any position, will be yieldingly supported in position, through the medium of the spring support above described.

The mower 25, which is of the usual or any preferred type, has a finger-bar and a sickle or cutter-bar thereon, the latter having pivotally engaged therewith a pitman 33 which extends inwardly and has its inner end pivotally engaged with an eccentric 34 carried on the one end of the aforesaid shaft 18. From this construction, it will be seen that as the shaft 18 is actuated, the cutter-bar will also be operated.

From the foregoing description of the construction of my improved device, the operation thereof will be readily understood and it will be seen that I have provided a device which is simple and durable in construction, inexpensive to manufacture and one which will be very efficient and useful in operation.

While I have particularly described the elements best adapted to perform the functions set forth, it is obvious that various changes in form, proportion and in the minor details of construction may be resorted to without departing from the spirit or sacrificing any of the principles of the invention.

Having thus described this invention, what is claimed is:—

1. In a device of the class described, the

combination with a vehicle; of a frame comprising a pair of bars intersecting one another intermediate their lengths and secured one to the other at their points of intersection and having their inner ends pivotally engaged with said vehicle, resilient means engaged with said frame at the point of intersection of said bars, and the vehicle to yieldingly support said frame in various adjusted positions with respect to the vehicle, a skid secured to the outer ends of the bars forming the frame, a mower pivotally carried on said skid and projecting laterally therefrom, means engaged with the mower to raise and lower the same to various positions with respect to the frame, and means for retaining said mower in any adjusted position.

2. In a device of the class described, the combination with a vehicle; of a pair of crossed bars pivotally secured at their inner ends to the vehicle and affording a frame substantially X-shaped in form, resilient means engaged with said bars at their points of intersection, a chain engaged with said spring means and adjustably connected to said object, whereby to yieldingly and adjustably support said frame on the vehicle, a skid carried on the outer ends of the bars forming said frame, a mower pivotally carried on said skid and projecting laterally therefrom, means in connection with said mower to manually raise and lower the same with respect to the frame, and means to retain said mower in any adjusted position.

In testimony whereof I hereunto affix my signature in the presence of two witnesses.

PEDER FURUSETH.
